UNITED STATES PATENT OFFICE

GEORGE GODDU, OF WINCHESTER, MASSACHUSETTS, ASSIGNOR TO THE LITTLEWAY PROCESS COMPANY, OF LYNN, MASSACHUSETTS, A CORPORATION OF MASSACHUSETTS

MANUFACTURE OF SHOES

Application filed July 3, 1924, Serial No. 724,135. Renewed July 5, 1929.

This invention relates to the manufacture of shoes, and in some of its important aspects has more particular reference to the manufacture of shoes of that type having an insole and 5 an outsole and in which the outsole is secured directly to the margin of the upper overlying the insole by suitable means, as by through-and-through stitches penetrating, at least at the time of their insertion, to the inside of the 10 shoe. In a co-pending application Serial No. 721,007, filed on June 19, 1924, I disclosed and claimed a novel method of making shoes of this type, having for an object to effect economies in the production of such shoes and, at 15 the same time to provide shoes of superior quality by dispensing with side lasting tacks either as permanent parts of the shoes or as temporary fastenings. In accordance with the procedure illustrated and described in 20 that application, the insole was provided with a lip on its outer or bottom face, either by channeling it or by securing to it a piece of material such as canvas tape, and in the progressive lasting of the sides of the shoe 25 the upper was fastened to the lip by fine wire staples. The shoe could thus be made without the extra operations involved in the use of temporary lasting tacks and without the delay required in waiting for the upper to 30 set in lasted shape when such tacks are used. The shoe, moreover, was of superior quality, since the upper was secured permanently in its original lasted condition to the insole by 35 fastenings of such a character and so applied as not to penetrate to the inner face of the insole nor to detract appreciably from the 40 flexibility of the shoe.

The present invention, in one important aspect, has in view still further economies 45 and improvements in the manufacture of shoes of the above-mentioned type. It is sometimes desired, for purposes of economy or in order to provide a more flexible shoe, to use an insole which is so thin or of such 50 quality that it cannot be provided with a channel lip which will successfully withstand the strain of the upper if the upper is fastened to it in the lasting of the shoe. Likewise, for the sake of economy or for other reasons, it may not be desired to attach a tape to the in-

sole to serve as a lip. To meet these conditions the present invention, in one important aspect, provides a novel method of making shoes in the practice of which the upper is initially yet permanently fastened while under 55 lasting strain to the intact substance or body of the insole, as distinguished from a lip or from any part weakened by a channel or other incision, by fastenings that are anchored in the insole without being clinched 60 on its inner face. To render the fastenings effective to hold the upper, the invention provides for anchoring them by directing them in curved paths within the substance of the insole. In accordance with the procedure 65 herein illustrated the fastenings are curved in such manner that their points are directed reversely toward the outer or bottom face of the insole without penetration of its inner face. The ends of the fastenings thus inserted may or may not emerge from the outer or 70 bottom face of the insole, since in either case they are entirely embedded in or covered by the shoe bottom materials after the outsole has been applied. 75

While in many of its aspects the invention is not limited as to the character of the fastenings utilized, it is considered preferable to use fine wire staples, since fastenings of that character have been found amply effective 80 for holding the upper in lasted position and at the same time do not detract appreciably from the flexibility of the shoe nor are otherwise objectionable as permanent parts of the shoe. 85

While the invention is illustrated and described with particular reference to the manufacture of shoes of the type hereinbefore mentioned, it is considered that in various aspects the invention may be utilized to advantage in the manufacture of shoes of various kinds; and the term "sole" is accordingly used in many of the claims in a generic sense to designate that part to which the upper is fastened in lasting, whether it be 90 the insole of some kinds of shoes or in other kinds of shoes the single sole or the outsole. 95

The invention will now be more particularly set forth by reference to the accompanying drawings and thereafter pointed 100

out in the claims. For convenience the drawings illustrate the practice of the method by the aid of operating instrumentalities which form part of a machine organization fully shown and described in my co-pending application Serial No. 724,136 filed on July 3, 1924, although it is to be understood that the invention is not dependent upon the use of instrumentalities of the particular character herein shown.

10 In the drawings—

Figs. 1, 2, 3 and 4 illustrate different steps of the method;

15 Fig. 5 is a perspective view of a portion of the side of a shoe after lasting;

Fig. 6 is a cross-sectional view of a portion of the shoe after the fastening of the outsole to the insole, and

20 Fig. 7 illustrates more clearly on an enlarged scale the shape of the staple in the shoe.

It will be understood that prior to the operations illustrated in Fig. 1 the insole *a* and the upper materials *b* are assembled on the 25 last, and in accordance with the usual practice the upper may then be pulled over at the toe and fastened by the pulling-over tacks. Thereafter the sides of the shoe are lasted by subjecting different portions of the upper 30 materials along the sides to lasting strain and fastening them in lasted position on the outer face of the insole. In practising the method by the aid of the instrumentalities herein shown the upper is pulled by a gripper 2, 35 first heightwise of the last and then inwardly over the insole, the shoe being positioned for these operations by the aid of a sole rest 4 and an edge gage 6. Thereafter the upper, while held yieldingly by the gripper, is 40 pressed down upon the outer face of the insole, as illustrated in Fig. 2, by overlaying means comprising a staple guiding member 8 and a staple deflector 10 which are moved as a unit in a direction inclined to the plane of 45 the insole to wrap the upper about the edge of the insole under lasting strain and to lay a portion of its margin in parallel relation to the outer face of the insole. While the upper is held under lasting strain, as herein 50 illustrated both by the gripper 2 and by the pressure of the overlaying means, a staple *c* of fine wire is driven through a portion of the upper which is in the line of the lasting strain by a staple driver 12 movable in a guideway 55 in the member 8. Figs. 3 and 4 illustrate successive stages in the driving of the staple into the shoe materials. The staple utilized has substantially straight leg portions, as shown in Fig. 2, and the driver 12 moves in 60 a direction or line at the same angle to the plane of the insole as the direction of the overlaying pressure applied by the members 8 and 10. The member 10 is in the path of the legs of the staple thus driven and is so 65 shaped and arranged as to act upon different

portions of the legs of the staple successively before the different respective portions enter the shoe materials to bend or deflect them in a positively predetermined degree out of the line of drive in planes herein illustrated as substantially perpendicular to the cross-bar of the staple, in such manner as to cause the legs of the staple to enter the shoe materials in substantially perpendicular relation to the plane of the insole and then to take curved paths in the materials. As herein shown the legs of the staple are bent throughout substantially their entire lengths in arcs of such radius that without penetrating to the inner face of the insole their ends are directed reversely toward its outer face, the legs forming substantially half circles in the shoe. In accordance with the practice herein illustrated the legs of the staples are turned outwardly toward the edge of the shoe bottom 85 from the points where they enter the insole.

It will be understood that after these operations have been performed in one location, the shoe is moved along to a different location and the same lasting operations are repeated. In this manner the sides of the shoe are lasted progressively, the upper being fastened securely and permanently in lasted position by the staples without opportunity for it to relax between the upper pulling and the fastening operations. It will be observed that the staples are driven into a portion of the insole, herein termed the intact substance thereof, which has not been weakened by any channel or other incision nor forms a projection from the body of the insole, and that secure anchorage for the legs of the staples is thus afforded. By reason of the accurate predetermined of the curvature of the legs of the staples independently of resistance of the shoe materials, it is feasible to utilize a comparatively thin and flexible insole without penetration of the fastenings entirely through the insole.

After the sides of the shoe have thus been 110 lasted, the toe and heel ends may be lasted in the usual manner, and thereafter the outsole *d* is applied and subjected to the usual sole laying pressure. If desired also a filler 115 *e* may be inserted between the insole and the outsole, as illustrated. After the sole laying operation the last is removed and the outsole is secured to the insole by through-and-through stitches *f* located between the row of staples and the edge of the 120 insole.

It will be appreciated that, among its different advantages, the invention effects substantial economies in that the operations incidental to the provision and use of a lip on the insole are dispensed with, while at the same time the manner of fastening the upper to the insole in shoes in which the upper, the insole and the outsole are in the relation to one another herein illustrated is such as 125 130

to avoid the presence of clinched metallic fastenings on the inner face of the insole in the locations of the side lasting tacks commonly used heretofore in shoes of that type.

5 The fact, moreover, that the upper is fastened under lasting strain to the intact substance of the insole contributes to the superior quality of the shoe by reason of the additional insurance afforded against any objectionable relaxation or displacement of the tensioned upper prior to the outsole securing operation. A further very advantageous characteristic of the shoe is that the ends of the metallic fastenings are directed 10 reversely toward the outsole, so that there is no danger in the wear of the shoe that the ends of these fastenings may work up into the interior of the shoe.

The herein-disclosed novel method of fastening per se and the product thereof are 20 claimed in a divisional application, Serial No. 291,881 filed on July 11, 1928.

Having described the invention and set forth fully how the method may be practised, what I claim as new and desire to secure by Letters Patent of the United States 25 is:

1. The method of making shoes which 30 comprises subjecting an upper to lasting strain to shape it over a last and to position it in lasted relation to a sole on the last, and while holding the upper under the lasting strain securing it initially yet permanently in lasted position by inserting a fastening 35 through the upper and the outer face of the sole in a direction transverse to the plane of the sole and anchoring the fastening in the intact substance of the sole without penetrating the inner face of the sole.

40 2. The method of making shoes which comprises pulling an upper successively in different locations along the sides of a shoe and laying it inwardly over the margin of the sole in lasted position, and after each of 45 the upper pulling and overlaying operations securing the portion of the upper which is under lasting strain to the sole by inserting a fastening through the upper and the plane bottom face of the sole into the intact substance of the sole and anchoring the fastening in said intact substance of the sole by directing it in a predetermined curved path before it arrives in position to penetrate the inner face of the sole.

55 3. The method of making shoes which comprises subjecting an upper to lasting strain to shape it over a last and to position it in lasted relation to a sole on the last, and 60 while holding the upper under the lasting strain fastening it initially yet permanently to the sole by inserting a fastening substantially in the line of strain through the upper and into the sole and anchoring the fastening 65 by directing it in a predetermined curved

path before it arrives in position to emerge from the sole.

4. The method of making shoes which comprises pulling different portions of an upper successively over a last and fastening the upper to a sole on the last in each location where the pull is applied, before pulling the upper in a different location, by inserting a fine wire staple through a portion of the upper located substantially in the line of the pulling strain and into the sole and anchoring the staple in the intact substance of the sole by directing its legs in predetermined curved paths before they arrive in position to emerge from the sole.

5. The method of making shoes which comprises subjecting different portions of an upper successively to lasting strain to shape the upper over a last and to position it in lasted relation to a sole on the last, and while holding each of said portions of the upper under lasting strain fastening it, before applying the strain in the next lasting location, by inserting a staple through the upper and into the sole in a direction transverse to the plane of the sole and anchoring the staple in the intact substance of the sole without penetrating the inner face of the sole.

6. The method of making shoes which 95 comprises subjecting different portions of an upper successively to lasting strain to shape the upper over a last and to position it in lasted relation to a sole on the last, and while holding each of said portions of the upper under lasting strain fastening it by inserting a staple through the upper and the outer face of the sole and anchoring the staple by curving its legs in the intact substance of the sole to direct their ends reversely toward the outer face of the sole without penetrating its inner face.

7. The method of making shoes which 100 comprises subjecting different portions of an upper successively to lasting strain to shape the upper over a last and to position it in lasted relation to a sole on the last, and while holding each of said portions of the upper under lasting strain fastening it initially yet permanently to the sole by inserting a metallic fastening through the upper and into the sole and anchoring the fastening by directing it in a path curved in predetermined degree from the point where it 105 enters the sole.

8. The method of making shoes which 110 comprises pulling an upper over a last and laying it inwardly over the outer face of a sole on the last by pressure applied in a direction inclined to the plane of the sole, and while holding the upper by said pressure securing it to the sole by driving a fastening in a direction also inclined to the plane of the sole and curving the fastening as it is 115 driven to anchor it within the intact sub-

stance of the sole without penetrating the inner face of the sole.

9. The method of making shoes of a type having an insole and an outsole, which comprises subjecting the upper in different locations successively along the sides of the shoe to lasting strain and securing it while under the lasting strain in each of said locations, before subjecting it to strain in another location, by inserting a metallic fastening through the upper and the outer face of the insole and anchoring the fastening in the intact substance of the insole without penetrating to the inner face of the insole, and thereafter applying the outsole over the insole and securing it directly to the margin of the upper overlying the insole.

10. The method of making shoes of a type having an insole and an outsole, which comprises subjecting the upper in different locations successively along the sides of the shoe to lasting strain and securing it while under the lasting strain in each of said locations by inserting a staple through the upper and the outer face of the insole and anchoring the staple within the intact substance of the insole by curving its legs substantially throughout their lengths in such degree as to direct their ends reversely toward the outer face of the insole, and thereafter applying the outsole over the insole and securing it to the insole by through-and-through stitches.

11. That improvement in methods of making shoes which consists in conforming an unlasted upper to the shape of a last and, while holding it so conformed, initially yet permanently fastening it to a sole by metallic fastenings anchored in the sole by deflection thereof effected entirely at that side of the work where the fastenings enter it.

In testimony whereof I have signed my name to this specification.

GEORGE GODDU.
